REVERSE CURRENT RESPONSIVE DEVICE

Paul J. Reifsneider, Springfield, Pa., assignor
to General Electric Company, a corporation of
New York

Application August 18, 1949, Serial No. 110,966

8 Claims. (Cl. 175—339)

1

The invention relates to reverse-current responsive devices and provides an improved multi-polar magnetic trip mechanism for circuit breakers of the direct-acting type having a self polarized armature operable by magnetic reaction between reversible magnetic poles with and without a time delay upon reversal of the current so as to be suitable for use in a protective system for multiple-operated direct-current generators or in other reverse-current time delay control service.

Hence one object of the present invention is to provide improved means for enabling a permanent magnet self polarized armature to effect an improved selective substantially instantaneous or an inverse time-delay retarded response dependent jointly upon the direction, magnitude and duration of the current.

Thus, whenever the direct-current reverses and exceeds a normal maximum reverse value substantially instantaneous response may be obtained. However, reverse currents of lesser values must persist for varying intervals inversely proportional to the value of the reverse current before the time delay retarded response can be obtained. In this way the polarized armature is enabled to ride over many transient current reversals without fully responding while still protecting against continuing unsafe reverse-current conditions.

Another object is to provide an improved inductive current-responsive flux-shifting means for preventing depolarization of the self polarized armature and thereby maintain the armature magnetically effective to respond in case an excessive rate of rise should cause the reverse current to exceed the normal maximum value before the armature could otherwise respond substantially instantaneously.

Another object is to provide for automatic reset of the polarized armature of the reverse-current trip mechanism immediately upon the tripping of the circuit breaker.

Further objects and advantages of the invention will appear in the following description of the accompanying drawing in which Fig. 1 is a side view of the improved selective instantaneous and time delay reverse-current responsive trip mechanism of the present invention applied to a circuit breaker; Fig. 2 is an enlarged sectional view on line 2—2 showing the permanent magnet polarized centrally-pivoted armature in co-operating relation with the depolarization preventing current-responsive inductive rings of the present invention and with the selective substantially instantaneous and time-delay mechanism operatively connected with the armature; and

2

Fig. 3 is an exploded perspective view partially in section indicating more clearly the structure and operating relation of the parts of the improved selective reverse-current trip mechanism.

5 As shown in Fig. 1, the reverse-current responsive trip mechanism indicated generally by the reference character 10 acts directly to trip the latch 11 of the circuit breaker indicated generally by the reference character 12 so as to open 10 the breaker substantially instantaneously when the reverse current exceeds a predetermined value and with an inverse time delay for reverse currents below said value. The reverse current trip mechanism 10 and the circuit breaker mechanism 12 may be mounted on a base 13 preferably formed of molded insulating material and provided with the connection terminals 14 and 15 at the opposite ends of the base 13 for connecting both the trip mechanism and the circuit breaker 20 contacts in the circuit to be protected.

The circuit breaker 12 as shown with its enclosing cover removed is of the well-known trip-free overcenter toggle-operated snap-action type, although it should be understood that the improved reverse current responsive mechanism 10 of the present invention may be applied to trip any suitable type of circuit breaker or in other control service. The circuit breaker 12 has a rectilinearly movable bridging contact 17 operable into and out of engagement with a pair of laterally spaced apart stationary contacts 18, one of which is directly behind the other in Fig. 1 and connected through the conductor 19 with the terminal 14 and the other of which is connected through the conductor 20 and the U-shaped loop conductor 21 of the trip mechanism 10 with the terminal 15 as shown.

30 The rectilinearly movable bridging contact 17 operates inside a pressure arc-suppressing chamber 23 formed in the block 24 of suitable arc-resisting material preferably moulded integral with base 13. The plunger 25 that carries the bridging contact 17 extends with a close running fit through the top of the block 24 and in order to obtain the required substantially rectilinear 35 movement is connected by the pivot pin 26 to one end of the lever 27 that in turn is pivoted by means of pin 28 on the guide link 29 that rotates about the stationary pin 30 having its ends fixed in parallel side frames 31 mounted by screws 32 on block 24 but the front one of which is not shown in Fig. 1 in order to reveal the operating parts carried therebetween.

40 The toggle links 33 and 34 extend between pivot pin 28 and pivot pin 35 that is carried by the 45 latched yoke member 36 having the latching face

37 engaged by the latching member 11. The yoke 36 is pivotally mounted on the stationary pin 38 so that when the latching face 37 is disengaged by the latch 11, the toggle links 33 and 34 can be moved bodily upwardly by the force exerted by the opening bias tension spring 40 having one end connected with pin 28 and the other end anchored on stationary pin 41. During the initial part of the upward movement of the toggle link, the tension spring 44, having one end connected to the outwardly bent end 45 of lever 27 and the other end connected to an anchoring clevis 46 seated in the frame 31, serves to maintain the bridging contact 17 in firm circuit-closing engagement with the pair of stationary contacts 18. However, as soon as the outwardly bent end 45 of lever 27 engages with the top of the recess 47 formed in the side frame 31, the continued upward movement of the toggle links 33 and 34 becomes effective to quickly separate the bridging contact 17 from the pair of stationary contacts 18. At the same time, the hump 48 on toggle link 33 engages with pivot pin 38 so as to buckle the toggle and thereby complete the snap action movement of the bridging contact 17 away from the pair of stationary contacts 18. When the toggle buckles, the yoke member 36 is moved automatically by spring 49 to return the face 37 into latching engagement with the latch 11.

In order to reclose the circuit breaker 12, the closing lever 50 is operated either manually or by a suitable closing solenoid (not shown) to pivot about its mounting pin 51 so as to engage the finger 52 with the reset pin 53 carried on the overhanging end of toggle link 33 and thereby return the toggle links to their straightened condition since the yoke member 36 has automatically reset the face 37 into latching engagement with the latch 11.

Spring 55 serves to return the closing lever 50 to the position in which it is shown in Fig. 1 after the closing operation is completed. Such re-latching of the trip member 36 and straightening of the toggle links 33 and 34 serves to move the pin 28 and guide links 29 so that spring 44 becomes effective to bias lever 27 to hold the bridging contact 17 in firm circuit-closing engagement with the pair of stationary contacts 18 through the agency of the plunger 25. With the circuit breaker mechanism 12 in the circuit-closing position as shown in Fig. 1, the finger 54 projecting from the toggle link moves spring 57 to operate a suitable enclosed auxiliary switch 58 that may be connected in a signal lamp circuit for indicating the closed condition of the breaker mechanism.

In order to trip the circuit breaker mechanism 12 upon a reversal of the current in the loop conductor 21, the improved reverse current responsive selective instantaneous and time delay multipolar magnetic tripping mechanism 10 is provided in accordance with the present invention. For this purpose a U-shaped magnetic yoke 60 is interlinked with one leg of the direct current U-shaped loop conductor 21 and provided with the pole pieces 61 and 62 to form oppositely aligned pairs of poles 63, 64, 65, 66 in quadrangular spaced-apart relation centrally of the loop. As a result, intersecting oblique flux paths are provided between the diagonally opposite pairs of poles 63, 66 and 64, 65 as will be evident from an inspection of Fig. 2.

A polarized magnetic armature 70 is centrally pivoted by means of a pair of pivot pins 71 adjustably mounted in the opposite legs of a U-

shaped support 72 that is secured to the pole piece 62 by means of the holding screws 73. The polarized armature 70 is formed with a central permanent magnet straight bar portion 75 having the polar extensions 76 and 77 of magnetic material at the opposite ends thereof and provided with a double-arm trip lever 78. The polar extensions 76 and 77 are suitably joined to the permanent magnet portion 75, preferably by soft soldering and the double-arm trip lever 78 is preferably formed of nonmagnetic material and likewise may be joined in a similar manner to form a unitary polarized armature assembly.

In order to provide for the central pivotal mounting of the unitary armature 70, the trip lever 78 is provided with a central rectangular cutout opening 79 into which a curved pivotal mounting spring member 80 is seated and provided with a central bearing hole for receiving the end of the mounting pivot 71 as shown in the perspective view of Fig. 3. A similar curved spring mounting bearing is similarly seated on the opposite side of the armature 70 for receiving a similar mounting pivot 71 so that the armature 70 is suspended for free pivotal movement therebetween. Thus, the polarized armature 70 can readily tilt from its full-line position to which it is biased by spring 81 and in which the polar extensions 76 and 77 are adjacent the diagonally opposite pair of poles 63 and 66 into its dotted-line position as shown in Fig. 2 in which the polar extensions engage with the diagonally opposite pair of poles 64 and 65. Since the centrally pivoted armature 70 has its pivot axis at the intersection of the oblique flux paths between the diagonally opposite pairs of poles 63, 66 and 64, 65, the polarized armature 70 will move from one path to the other, i. e., from one polar position to another upon a reversal of the current in the conductor 21 due to the magnetic reaction of the permanent magnet 75 with the flux produced in the magnetic yoke 60 and the pole pieces 61, 62 by the reverse current flow through the conductor 21. Thus the magnetomotive forces set up by current flow in the conductor 21 and by the permanent magnet always tend to become cumulative, or in other words the polarized armature 70 always seeks the path of least reluctance as is well known in the art.

The curved trip arm 82 of the lever 78 engages with a finger 83 extending from the circuit breaker latch 11 that is pivotally mounted on the shaft 84 so as to directly turn the latch 11 about the shaft 84 to disengage the latch 11 from the latch face 37 and thereby trip breaker 10 when the polarized armature 70 is operated into its dotted-line position shown in Fig. 2. The latch 11 is biased to return to the latching position in which it is shown in Fig. 1 by the spring 85.

In order to enable the reverse current responsive trip mechanism 10 to ride over many transient current reversals without tripping, a time-delay mechanism indicated generally by the reference character 90 is provided with the resilient operating spring connection 101 for flexing to permit a substantially instantaneous movement of the polarized armature 70 from its full-line or normal current position when the reversed current exceeds a predetermined value but retarding the movement of the armature to its dotted-line or reverse current tripping position as shown in Fig. 2 when the reverse current re-

mains below the predetermined value. In the form shown, the time-delay mechanism 90 is of the escapement type having a pallet 91 oscillating on the verge 92 upon rotation of the escapement wheel 93 that is turned by engagement of the gear lever 94 with the driving pinion 85. All of these operating parts of the time-delay mechanism 90 are mounted inside the channel frame 98 that is secured to one leg of the magnetic yoke 66 by means of the mounting screws 86. Rivets 97 serve to secure the pole piece 61 to the yoke 66 as shown in Fig. 2. Thus the pivot axis 100 of the gear lever 94 is in quadrature with the pivot axis of the polarized armature 70 and in order to operatively interconnect the two, the spring member 101 is coiled around the pivot axis 100 with one end anchored in a suitable hole 102 formed in the gear lever 94 and the other end hooked into a suitable hole 103 formed in the reset arm 105 extending from the armature trip lever 78 with an intermediate section of the spring 101 firmly seated upon the projection 106 from the gear lever 94 due to the torque exerted by the coiled portion of the spring.

Thus when polarized armature 70 tends to tilt from its full-line or normal current position to its dotted-line or reverse current position shown in Fig. 2, the spring 101 serves to retard or delay the movement of the armature by rotating the gear lever 94 about shaft 100 and thereby turn the escapement wheel 93 to oscillate the pallet 91 as long as the escapement portion of wheel 93 engages therewith and the force exerted by the armature 70 is below that required to lift the section of spring 101 away from the projection 106. Consequently, with the force exerted by the polarized armature 70 dependent upon the value of the reverse current below a predetermined normal value an inverse time delay is obtained before the wheel 93 runs free from the pallet 91 to allow trip arm 82 to strike finger 83 and trip the breaker 10. However, whenever the reverse current exceeds the predetermined normal value, spring 101 yields and thereby provides for substantially instantaneous tripping operation of the polarized armature 70 as long as the armature 70 is maintained self polarized by the permanent magnet 75.

When the polarized armature 70 is in its dotted-line or reverse current tripping position shown in Fig. 2, the permanent magnetization thereof tends to hold the armature in the dotted line position engaging the poles 64 and 65 despite the return bias of the calibrating spring 81. In order to automatically reset the armature 70 into its full-line or normal current position as soon as the tripping of circuit breaker 10 is accomplished, a lever 107 is pivotally mounted on the pivot axis 30 and provided with an overhanging plate 108 to be engaged by the toggle link 29 during the tripping of the breaker. The finger 109 is carried at the other end of the lever 107 into engagement with the rounded end of the reset lever 105 so as to forceably break away the polarized armature 70 from its dotted-line position shown in Fig. 2 and enable the calibrating spring 81 to return armature 70 to its full-line position.

In case an excessive rate of rise should cause the reverse current to materially exceed the normal maximum value before the armature moves from the full line position, the resulting magnetomotive force produced between the diagonally opposite pair of poles 63 and 66 will be in opposition to the magnetomotive force of the permanent magnet 75 and may materially pre-

dominate thereover to such an extent as to permanently reduce the magnetization of the permanent magnet so that it becomes practically ineffective or, in other words, depolarize the magnet. In order to prevent such depolarization and thereby maintain the self polarized armature 70 magnetically effective to flex the retarding spring connection 101, the diagonally opposite pair of poles 63, 66 are each provided with inductive current-conducting flux-shifting means indicated generally by the reference character 110 that serves to prevent depolarization of the permanent magnet 75. In the form shown in cross-section in Fig. 2, a facing 111 of conducting material such as copper is provided for the pole 63 and an additional current-conducting ring section 112 encircles the pole 63 with these parts suitably joined to the pole as by soldering or the like. Thus when the excessively high rate of rise of reverse-current in conductor 21 tends to reverse the flux through the poles 63 and 66 very quickly, the eddy currents induced in both the facing plate 111 and the ring 112 serve to shift the flux from these poles into the other poles and thereby maintain the magnetic force effective to move the polarized armature 70 to the other flux path in which the magnetomotive force produced by the reverse-current in conductor 21 is cumulative with that of the permanent magnet 75. Furthermore, the facing 111 serves to space the polar projections 76 away from the pole 63 so as to provide a nonmagnetic gap of substantial reluctance therebetween. This is also true of the pole 66 which is provided with a facing 113 and a ring 114 of conducting material identical in structure and formation. Thus, whenever an excessively high rate of rise causes the reverse-current to reach quickly an abnormally high value, depolarization of the permanent magnet 75 is effectively prevented by the flux-shifting action of the inductive current-responsive means 111, 112, 113, and 114 and the armature 70 is maintained magnetically effective to flex the retarding spring 101.

The reverse-current circuit breaker with the improved tripping mechanism shown in Figs. 1, 2, and 3 is particularly adapted for operation in a multiple-connected direct-current generator protective system such, for example, as are used on aircraft in which each generator is driven at widely varying speeds by a corresponding one of the aircraft propelling engines. In such service each generator may be connected to a common bus through the reverse-current circuit breaker 12 in order to protect the generator from damage in case the driving motor should suddenly reduce its speed or stall or a short-circuit or ground should occur. In case of only a transient reduction of the generator operating speed such that the magnitude and duration of the reverse current do not exceed predetermined values, the time-delay mechanism 90 will enable the reverse-current responsive trip mechanism 10 to ride over the disturbance without tripping the circuit breaker mechanism 12. However, in case the generator speed should decrease more rapidly than can be taken care of by the voltage regulator so that the reverse-current exceeds a predetermined normal value, then instantaneous tripping of circuit breaker 12 by trip mechanism 10 will occur due to the flexing of the spring connection 101 between the time mechanism 90 and the tilting armature 70. In the event of a short circuit or ground whereby a large value of reverse-current is obtained practically instanta-

neously, the improved flux-shifting means 111, 112, 113 and 114 will effectively prevent depolarization of the permanent magnet 75 thereby maintaining the armature 76 magnetically effective at all times. Thus it will be seen that the improvements of the present invention enable the reverse-current trip mechanism 18 to successfully meet all of the normal and abnormal instantaneous and time delay operating conditions.

What I claim as new and desire to secure by Letters Patent of the United States is:

1. A reverse-current responsive device having in combination, a direct-current conductor having an interlinking magnetic yoke provided with pole pieces to form oppositely aligned pairs of reversible poles, a centrally pivoted permanent magnet armature having each end thereof magnetically operable between a corresponding pair of said poles when the current in the conductor reverses, and inductive current-responsive conducting rings separately encircling a diagonally spaced one of each pair of poles for shifting the flux to the other poles to prevent depolarization of the permanent magnet armature and thereby maintain the armature magnetically effective when the rate of rise of reverse current becomes excessive.

2. A reverse-current responsive device having in combination, a direct-current conductor having an interlinked magnetic yoke provided with pole pieces in opposing alignment to form obliquely spaced pairs of magnetically opposite poles, a centrally pivoted permanent magnet armature having polar extensions at the ends thereof operable by magnetic reaction away from one of said pair of poles towards the other pair of poles when the current in the conductor reverses, a facing of conducting material on each of said one pair of poles for spacing said polar extensions a predetermined distance therefrom, and inductive current-responsive rings separately encircling each of said one pair of poles for cooperating with said conducting facings to shift the flux to the other poles to prevent depolarization of the permanent magnet armature and thereby maintain the armature magnetically effective when the rate of rise of reverse current becomes excessive.

3. In combination, a direct-current conductor having magnetic means providing a plurality of pairs of poles reversible in polarity upon reversal of the current in the conductor, a permanent magnet polarized armature movable from one to another pair of said poles upon reversal of the polarity thereof, time-delay mechanism having a resilient connection with the armature for retarding the movement of the armature between said poles and flexing to render said time-delay mechanism ineffective when the reverse current in the conductor exceeds a predetermined value and inductive current responsive means interlinking each of said one pair of poles for maintaining the armature magnetically effective to flex said resilient connection.

4. In combination, a permanent magnet armature provided with pivotal mounting means, direct current electromagnetic means for tilting the armature between two angular positions upon reversal of the current, a time-delay mechanism having a resilient connection with the armature to provide a time-delay in the tilting of the armature from one to the other of said positions when the current reverses and said connection flexing to provide for substantially instantaneous operation of the armature when the reverse current exceeds a predetermined value, and inductive cur-

rent responsive means engageable by the end of the armature in said one position for preventing depolarization of the permanent magnet of the armature and maintaining the armature magnetically effective to flex said resilient connection when the rate of rise of the reverse current becomes excessive.

5. A reverse-current responsive device having in combination a direct-current conductor having an interlinked iron yoke provided with pole pieces shaped to form aligned pairs of opposite poles, a centrally pivoted permanent bar magnet having its pivot axis equi-distant from each of said poles and provided with polar extensions in cooperating attractive relation with diagonally opposite pairs of said poles to be moved therebetween when the current in the conductor reverses, and separate conducting rings mounted on each of a diagonal pair of said poles for engagement by said polar extensions to prevent depolarization of said bar magnet and thereby maintain the magnet effective for movement when the rate of rise of reverse current through said conductor becomes excessive.

25 6. A reverse-current responsive device having in combination, a direct-current conductor having an interlinked magnetic yoke provided with pole pieces in opposing alignment to form obliquely spaced pairs of magnetically opposite poles, a centrally pivoted permanent magnetic armature operable magnetically away from one pair of said poles towards the other pair of said poles when the current in the conductor reverses, current responsive members in separate inductive relation with the flux in each of said one pair of poles for shifting the flux to the other poles to prevent depolarization of the permanent magnet armature and thereby maintain the armature magnetically effective when the rate of rise of reverse current becomes excessive, and time-delay mechanism having a resilient connection with the armature to retard the movement of the armature away from said one pair of poles toward the other pair of poles, said connection yielding to provide for substantially instantaneous movement of the armature when the reverse current exceeds a predetermined value.

7. A reverse-current responsive device having in combination, a direct-current conductor having an interlinked magnetic yoke provided with pole pieces to form obliquely intersecting flux paths between diagonally opposite pairs of said poles, a centrally pivoted permanent magnet armature having its axis at the intersection of said flux paths for tilting movement from one path to the other path when the current in the conductor reverses, an escapement timing mechanism having a pivotally mounted operating gear member with its axis in quadrature with the axis of said armature, operating connections between said gear member and said armature including a spring to provide an inverse time delay in the tilting of the armature between said paths as long as the reverse current in the conductor is below a predetermined value and flexing to render said time-delay mechanism ineffective when the reverse current in the conductor exceeds said value, and inductive current responsive means interlinking said one path for maintaining the armature magnetically effective to flex said spring when the rate of rise of reverse current becomes excessive.

8. A reverse-current tripping device having in combination, a direct-current conductor in the form of a U-shaped loop, a magnetic yoke inter-

linked with one leg of the loop and provided with pole pieces to form oppositely aligned pairs of poles centrally of the loop, a centrally pivoted permanent magnet armature having its axis transverse the loop for tilting the armature away from one pair of said poles into engagement with the other pair of said poles when the current in the conductor loop reverses, a double arm lever carried by the armature and having a tripping arm extending from one side of the loop and a restraining arm extending from the other side of the loop, and an escapement time-delay mechanism having a pivoted gear operating member with its axis normal to the loop and provided with operating connections including a spring connected with said retarding arm to retard the tilting of the armature between said poles and yielding to render said time delay mechanism ineffective when the reverse-current in the conductor exceeds a predetermined value, and inductive current responsive means interlinking

5

each of said one pair of poles for maintaining the armature magnetically effective to flex said spring when the rate of rise of reverse current becomes excessive.
